TUBE HOLDER FOR USE WITH A COMBINED SPLASH GUARD AND HOLDER FOR BATH-ROOM ACCESSORIES

Stephen J. Baumrind, Charleston, S.C., assignor of a fractional part interest to Larry Harold Kline, Charleston, S.C.

Filed Mar. 2, 1973, Ser. No. 337,389

Term of patent 14 years

Int. Cl. D6—06

U.S. Cl. D6—87

FIG. 2

FIG. 1

FIG. 4

FIG. 3

FIG. 1 is a front elevational view of a tube holder for use with a combined splash guard and holder for bathroom accessories, showing my new design;

FIG. 2 is a sectional view taken along lines 2—2 of FIG. 1;

FIG. 3 is a sectional view taken along lines 3—3 of FIG. 1; and

FIG. 4 is a front perspective view of the tube holder.

I claim:

The ornamental design for a tube holder for use with a combined splash guard and holder for bathroom accessories, substantially as shown and described.
